P.A.

(57) CLAIM

The ornamental design for a badge, as shown and described.

DESCRIPTION

FIG. 1 is a top plan view of the badge showing my new design;

FIG. 2 is a bottom plan view thereof;

FIG. 3 is a front view thereof;

FIG. 4 is a rear view thereof;

FIG. 5 is a left side view thereof; and,

FIG. 6 is a right side view.

The broken line showing of environment in FIG. 1 is included for the purpose of illustrating only and forms no part of the claimed design.

1 Claim, 2 Drawing Sheets

CERTIFICATE OF CORRECTION

PATENT NO. : Des. 566,645 S
APPLICATION NO. : 29/198709
DATED : April 15, 2008
INVENTOR(S) : Niebuhr

It is certified that error appears in the above-identified patent and that said Letters Patent is hereby corrected as shown below:

In the Drawings

Delete drawing sheets 1-2 and substitute the two sheets of drawings with the attached two REPLACEMENT SHEETS of drawings.

Signed and Sealed this

Twenty-first Day of April, 2009

JOHN DOLL
Acting Director of the United States Patent and Trademark Office
